Primary Examiner—Philip S. Hyder

[57] CLAIM

The ornamental design for a shoe carrier, as shown and described.

DESCRIPTION

FIG. 1 is a front elevational view of a shoe carrier showing my new design, wherein the rear elevational view is a mirror image thereof;

FIG. 2 is a view of the top with the strap;

FIG. 3 is a side view thereof;

FIG. 4 is a view of the bottom with the zipper;

FIG. 5 is a perspective view of the shoe carrier; and

FIG. 6 is a perspective view of the bottom of the shoe carrier, shown in an open position.
